RAILWAY TRAFFIC CONTROLLING
APPARATUS

Howard A. Thompson, Edgewood, Pa., assignor to
The Union Switch & Signal Company, Swiss-
vale, Pa., a corporation of Pennsylvania

Application February 19, 1944, Serial No. 523,065

7 Claims. (Cl. 246—38)

1

My invention relates to railway traffic controlling apparatus, and particularly to apparatus employing track circuits supplied with periodical-
ly interrupted or coded current for controlling wayside and/or cab signals.

The principal object of my invention is to im-
prove the shunting sensitivity of track circuits of
the type described.

Another object of my invention is the provision
of means for supplying to a coded track circuit a
high voltage impulse during the "on" period of
each code cycle in a way which does not increase
wear on the contacts of the coding relays.

A further object of my invention is to provide
novel means for checking that a high voltage im-
pulse is actually present during the "on" period
of each code cycle.

According to my invention, I connect the sec-
ondary winding of an impulse transformer in
series with the track battery from which coded
current is normally supplied to the track circuit,
and I energize the secondary winding of this
transformer over a contact of the relay which
codes the track circuit energy in a manner to
cause the transformer to supply to the track cir-
cuit during the "on" period of each code cycle a
high voltage impulse of less duration than the
"on" period of the code cycle, whereby the cod-
ing relay contacts do not interrupt the high volt-
age energy. I further connect in series with the
track battery and the secondary winding of the
impulse transformer the one winding of a two
winding high voltage checking relay and a front
contact of a first repeater of this checking relay.
The other winding of the high voltage relay is
constantly connected to a source of direct current,
and the parts are so proportioned that when said
one winding is deenergized the relay will close a
normal contact, but that, each time a high volt-
age impulse is supplied to the track circuit the
resultant energization of said one winding by this
impulse will cause the relay to close a reverse
contact. A second repeater of the checking relay
is energized over said reverse contact in such
manner that this relay will remain continuously
energized as long as said high voltage relay oper-
ates its contacts in step with the code, and said
first repeater relay is energized over said normal
contact and a front contact of said second repeater
relay in such manner that it will remain
continuously energized as long as said second re-
lay is energized and said high voltage relay con-
tinues to operate its contacts in step with the
code.

In an alternative arrangement, I employ in 55

2

place of the high voltage relay at the battery end
of the track circuit and the two repeaters of this
relay for checking that a high voltage impulse is
being supplied to the track circuit during each
"on" period of the code in the intended manner,
another high voltage relay having its one wind-
ing connected in multiple with the track relay
and its other winding connected to a suitable
source of current over a stick circuit including its
own front contact and a contact of the track re-
lay. This latter relay performs the same func-
tions that are performed by the track relay in the
arrangement first described.

Other objects and characteristic features of my
invention will become apparent as the description
proceeds.

I shall describe two forms of signaling systems
embodying my invention, and shall then point out
the novel features thereof in claims.

20 In the accompanying drawings, Fig. 1 is a
diagrammatic view showing one form of appara-
tus embodying my invention. Fig. 2 is a diagram-
matic view showing the nature of the track circuit
current obtained with the apparatus shown in
25 Fig. 1. Fig. 3 is a view similar to Fig. 1 showing a
modification of the apparatus illustrated in Fig.
1, and also embodying my invention. Fig. 4 is a
diagrammatic view showing the nature of the
track circuit current with the apparatus shown
30 in Fig. 3.

Similar reference characters refer to similar
parts in each of the several views.

Referring first to Fig. 1, the reference charac-
ters 1 and 1a designate the track rails of a stretch
35 of railway track over which traffic normally
moves in the direction indicated by the arrow,
that is to say, from left to right in the drawings.
These rails are divided by means of insulated
joints 2 into blocks, only one of which E—G is
40 shown complete in the drawings, and this block,
in turn, is further divided at point F by means of
other insulated joints 2 to form two track sec-
tions 1T and A1T.

Traffic entering each block is controlled by a
45 signal designated by the reference character S
with a distinguishing suffix corresponding to the
location. These signals may be of any suitable
type, but in the well known form here shown
these signals are color light signals and each com-
50 prises a red lamp R, a yellow lamp Y, and a green
lamp G, which lamps when illuminated indicate
"stop," "approach" and "clear," respectively.

Each track section is provided with a track cir-
cuit comprising a code following track relay con-
nected across the rails at the entering end of the

section, and means located at the leaving end of the section for supplying to the rails of the section coded direct current the code frequency of which is controlled by traffic conditions in advance.

Each code following track relay is designated by the reference character R with a prefix corresponding to the reference character for the associated section, and may be of any suitable type capable of operating its contacts in step 10 with the pulses of coded current supplied to the rails. In actual practice each of these relays will usually be of the biased polar type because of the greater sensitivity of this type of relay.

The means located at the leaving end of each section for supplying coded current to the rails of the associated section varies slightly according as these means are disposed at a signal location or at a cut section location. Referring particularly to the means located at the signal location G, which means are typical of the means located at each of the other signal locations, these means in the form here illustrated comprise a battery 4 connected across the rails in series with the front contact 5 of a code repeater relay 1CTM, a current limiting resistance 6, the secondary winding 7 of a transformer TG, the one winding 8 of a two winding high voltage polar stick checking relay 1HVR, and the front contact 9-9a of a first repeater relay 1HVBSA of the associated checking relay.

The code repeater relay 1CTM may be controlled through the medium of the track relay for the section next in advance in a well known manner not shown to cause it to operate its contacts 5 and 11 at one or another of the usual plurality of code rates. Selection among these code rates, which rates in actual practice in a three block signaling system will usually comprise 75 or 180 times per minute depending upon whether the block to the right of block E-G is occupied or unoccupied, may be made by the usual decoding apparatus 10 controlled by the track relay A2TR for the track section A2T. It will be seen, therefore, that when relay 1CTM is operating, the resultant operation of its contact 5 will act to interrupt or code the current supplied by the associated track battery 4 at 75 or 180 times per minute depending upon whether the block to the right of section E-G is occupied or unoccupied. Each interruption is of such duration that the resulting code will consist of code cycles each comprising substantially equal "on" and "off" periods.

The contact 11 of relay 1CTM controls the supply of current to an energizing circuit for the primary winding 12 of transformer TG. This energizing circuit includes in addition to the contact 11, a suitable source of current the positive and negative terminals of which are designated B and C, respectively, and a condenser 13 connected in multiple with the primary winding 12. It will be seen, therefore, that each time relay 1CTM closes its back contact 11, energy will be stored in the magnetic circuit of transformer TG and also in condenser 13, whereas each time relay 1CTM opens contact 11, the energy stored in the transformer and condenser will cause a relatively high electromotive force to be induced in the secondary winding 7 of transformer TG. The contacts 5 and 11 of relay 1CTM are so adjusted that this induced electromotive force will be initiated immediately after the closing of contact 5 and will be substantially expended before contact 5 again opens, and it follows that

with the parts arranged in this manner a high voltage impulse will be impressed on the rails of the associated section during each "on" period of the code, but that this electromotive force will not increase the wear on the contacts of relay 1CTM since these contacts do not interrupt the circuit during the presence of this impulse. It will be obvious, of course, that a voltage will also be induced in secondary winding 7 of transformer TG each time the energizing circuit for primary winding 12 becomes closed at contact 11, but due to the previously referred to adjustment of the contacts 5 and 11, and the time constants of the circuit, the magnitude of this electromotive force will be negligible insofar as the operation of the contact 5 is concerned, and no appreciable voltage will be impressed on the rails due to the closing of the contact 11. The nature of the resulting code is illustrated diagrammatically in Fig. 2, where curve b represents the approach or 75 code and curve a represents the clear or 180 code.

The winding 15 of the high voltage relay 1HVR is constantly energized by an associated battery 16, and the parts of this relay are so proportioned that when the winding 15 only is energized, as will be the case during the "off" periods of the code, the contact 17-17a will become closed. However, when the winding 8 is also energized, as will be the case during the "on" periods of the code, a flux is set up in the core of the relay by the current flowing in the winding 8 which flux opposes that due to the current flowing in winding 15, and the parts are further so proportioned that under these conditions the relay will close its contact 17-17b if the high voltage impulse is present but will retain its contact 17-17a closed if the high voltage impulse is absent. It follows, therefore, that the relay 1HVR will alternately open and close its contacts 17-17a and 17-17b in step with the coded current supplied to the rails 1 and 4a if the high voltage impulse is present during each "on" period of the code, but will retain its contacts 17-17a continuously closed if this high voltage impulse is absent.

The repeater relay 1HVBSA referred to hereinbefore is energized over a circuit which passes from terminal B of the source through contact 17-17a of relay 1HVR, a front contact 18 of a second repeater relay 1HVFSR and a resistance 19 connected in multiple with the winding of relay 1HVBSA to terminal C. The second repeater relay 1HVFSR, in turn, is energized over a circuit which passes from terminal B through contact 17-17b of relay 1HVR, and a condenser 20 connected in multiple with the winding of relay 1HVFSR to terminal C. It will be seen, therefore, that when relay 1HVR is operating, relay 1HVFSR will become energized each time contact 17-17b of relay 1HVR becomes closed. The condenser 20 renders the relay 1HVFSR slow to release, and the parts are so proportioned that relay 1HVFSR will maintain its front contact 18 continuously closed as long as relay 1HVR continues to alternately open and close its contacts at any one of the usual code rates.

As long as contact 18 of relay 1HVFSR remains closed, relay 1HVBSA will become energized each time relay 1HVR closes its contact 17-17a, and the relay 1HVBSA is rendered sufficiently slow releasing by the resistance 19 so that it will maintain its front contact continuously closed as long as relay 1HVR continues to follow the code.

It will be noted that the snub or closed circuit

ate at the 75 code rate, and signal SE will thereupon display its approach aspect.

The parts will remain in the positions just described until the train vacates the block of which section A2T forms a part. When this happens, the 75 code energy will be supplied to section A2T and track relay A2TR will follow this code and will act through the decoding apparatus 10 to cause signal SG to display its approach aspect. Furthermore, relay 1CTM will start to operate at the rate of 180 times a minute, and will thus cause 180 code to be supplied to section 1T, and hence to section A1T, whereupon signal SE will display its proceed aspect.

When the train vacates the block next in advance of the block of which section A2T forms a part, signal SG will display its proceed aspect and all parts will be restored to the positions in which they are shown in the drawings.

It should be particularly pointed out that with the apparatus constructed in the manner described, the presence of the high voltage impulse during the "on" period of each code cycle acts to break down any high resistance film or coating which may be present on the rails, thereby insuring a shunting effect of the wheels and axles of a car or train under conditions where a lower voltage would be insufficient. The magnitude of the high voltage impulses may be made many times the usual track circuit voltage, and since no part of the high voltage impulse is present at the time the coding contacts of the various coding relays are either opening or closing, the presence of these impulses does not produce additional wear on these contacts. It might also be mentioned that since a high voltage impulse is present during each "on" period of the code, these impulses are available to break down the resistance of the wheel to rail contacts as the car or train moves from point to point along the track.

It should also be particularly pointed out that with the apparatus constructed in the manner just described if the high voltage impulse fails for any reason, the resultant underenergization of the winding 8 of the associated high voltage relay will result in the failure of this relay to operate its contacts in step with the code, and will thus cause the associated BSA checking relay to become deenergized. The deenergization of this relay will interrupt the track circuit at its front contact 9-9a, and will thus cut off the supply of coded energy to the track relay. This will result in the signals moving to their stop positions so that the failure will be sure to be quickly detected.

Referring now to Fig. 3, I have here shown an alternative arrangement of circuits in which an auxiliary code following repeater relay 1CTMM of relay 1CTM is provided at location G for controlling the energization of the primary winding 12 of transformer TG, and a similar repeater relay 1TM controlled by an auxiliary track relay 1TRA presently to be described is provided at location F for controlling the energization of the secondary winding 12 of transformer TF. The energizing circuits for relays 1CTMM and 1TM are obvious from an inspection of the drawings, and it will be apparent that each time relay 1CTM or auxiliary track relay 1TRA becomes energized, the associated repeater relay will become energized at the expiration of a short time interval thereafter. The primary winding 12 of transformer TG is energized over back contact 22 of relay 1CTMM, while that of transformer TF is energized over front contact 22 of relay 1TM be-

60 70 75

cause of the fact that back contact coding is employed at location F, as pointed out hereinbefore. With this arrangement, the energizing circuits for the primary windings of the transformers TG and 5 TF will not become interrupted until the expiration of a short time interval after the "on" period of the code is established by the closing of the front contact 5 of relay 1CTM or the back contact 5 of relay 1TRA, and it follows therefore that 10 the high voltage impulse will not be established until a short period after the start of the "on" period of each code cycle. This is shown diagrammatically in Fig. 4. This arrangement provides more positive action and consequently more 15 positive protection against burning of the contacts than is provided with the apparatus shown in Fig. 1 as a consequence of the fact that the high voltage impulse is initiated substantially simultaneously with the establishment of the 20 "on" period of the code.

Furthermore, in the alternative arrangement of circuits shown in Fig. 3, I employ in place of the high voltage checking relay and the associated front and back contact repeaters of these 25 relays at the battery end of each track circuit to check that a high voltage impulse is being supplied to the associated track circuit during each "on" period of the code in the intended manner, an auxiliary track relay located at the track relay end of the track circuit. These auxiliary track relays are designated by the same reference characters as the reference characters for the associated track relay with the suffix A, and may be generally similar to the track relays except for 30 the fact that each relay is provided with two windings. The winding 8 of each of these auxiliary relays is connected in multiple with the winding of the associated track relay, while the other winding 15 of each of these auxiliary relays 35 is energized over a stick circuit which includes a battery 26, a front contact 24 of the associated track relay and its own front contact 25. The parts of each of these auxiliary relays are so proportioned that the relay will become energized 40 to a sufficient extent to cause it to close its front contacts during each "on" period of the code if and only if the high voltage impulse is present, and that when either one of these relays closes its front contact 25, the energy supplied to its 45 winding 15 over the associated stick circuit will then be sufficient to retain the front contacts closed during the remainder of the "on" period which caused the contacts to become closed. If the stick circuits were not provided, the auxiliary 50 relays would be only momentarily energized during the high voltage impulse, and the stick circuits provide a means for insuring that the front and back contacts of the auxiliary track relays will be closed for approximately equal periods of time.

The auxiliary track relays may be utilized to perform the functions that are performed by the regular track relays in Fig. 1, and when so used, if the high voltage impulse is not present during 55 the "on" periods of the code, the auxiliary relays will fail to operate. This will cause the signals to indicate stop and will thus result in immediate detection of the failure.

The operation as a whole of the apparatus shown in Fig. 3 is generally similar to the operation of the apparatus shown in Fig. 1, and it is accordingly believed that this operation will be apparent from the foregoing description and from an inspection of the drawings without further detailed description.

which is provided for relay $A1HVFSA$ to render it slow releasing comprises a condenser, while that provided for relay $A1HVBSA$ comprises a resistor. The reason for this difference in the snubs for the two relays is that the contact $17-17a$ of relay $A1HVR$ is closed for a shorter portion of each code cycle than the contact $17-17b$, and a resistor snub will not provide a sufficiently slow release time for the relay $A1HVFSA$.

It will also be noted that while relays $A1HVFSA$ and $A1HVBSA$ will both be energized as long as relay $A1HVR$ follows the code, if relay $A1HVR$ stops following the code for any reason relay $A1HVBSA$ will become deenergized and will open its front contact $9-9a$ and close its back contact $9-9b$. The opening of contact $9-9a$ will disconnect the battery 4 and secondary winding 7 of transformer TG from the track circuit, while the closing of back contact $9-9b$ will complete a restoring circuit for relay $A1HVR$ passing from battery 4 through resistor 6 , secondary winding 7 of transformer TG , winding 8 of relay $A1HVR$, back contact $9-9b$ of relay $A1HVBSA$ and contact 5 of relay $A1CTM$ to battery 4 . This latter circuit permits the equipment to reset itself should the coding action of relay $A1CTM$ be stopped for any reason.

Referring now to the cut section location F , the means here shown for supplying coded current to the rails of section $A1T$ is identical with that just described at location G for supplying coded current to the rails of section $A1T$ except for the fact that the coding action at this location instead of being effected by means of a code repeater relay is effected by the track relay $A1TR$ which functions to repeat the code to section $A1T$. It is believed to be unnecessary therefore to describe this means in detail. It should be noted, however, that the contact 5 of relay $A1TR$ which effects the coding of the track circuit energy is a back contact, while the contact 11 of relay $A1TR$ which controls the energization of the primary winding 12 of transformer TF is a front contact so that the "on" periods of the code in section $A1T$ occur during the "off" period of the code in section $A1T$. The use of a back contact of the track relay at the cut section location instead of a front contact to repeat the code is a well-known expedient to minimize code distortion, and for the purpose of my present invention it is immaterial whether a back or a front contact is employed.

The track relays $A1TR$ and $A2TR$ control the associated signals SE and SG through the medium of suitable decoding apparatus 10 . This decoding apparatus may, for example, be similar to that shown and described in Letters Patent of the United States No. 2,218,120, granted to Frank H. Nicholson and Leslie R. Allison on October 15, 1940, for Railway traffic controlling apparatus, and it is believed, therefore, that for purposes of the present application it is sufficient to point out that the lamp G , Y , or R of these signals will be lit to indicate "clear," "approach," or "stop" according as the associated track relay is supplied with 180 code, 75 code, or no code.

As shown in the drawings, sections $A1T$, $A1T$ and $A2T$ are all unoccupied, and assuming that the section next in advance of section $A2T$ is also unoccupied, all three of the sections $A1T$, $A1T$ and $A2T$ will be supplied with 180 code energy. Signals SG and SE will therefore both indicate proceed.

In explaining the operation of the apparatus

as a whole, I shall assume that a train moves from left to right over the stretch of track shown in the drawings. When the train enters section $A1T$, the train shunt will cut off the supply of coded energy to the track relay $A1TR$, and this track relay will therefore become deenergized and will cause signal SE to display its stop aspect.

When the train enters section $A1T$, track relay $A1TR$ will become deenergized. This will cut off the supply of coded current to section $A1T$ and also to winding 8 of relay $A1HVR$, and contact $17-17a$ of relay $A1HVR$ will therefore become closed, so that relay $A1HVFSA$ will now become deenergized and will deenergize relay $A1HVBSA$. The deenergization of relay $A1HVBSA$ will complete the restoring circuit for winding 8 of relay $A1HVR$, but since this circuit will not be supplied with high voltage impulses under these conditions, contact $17-17a$ of relay $A1HVR$ will remain continuously closed. Furthermore, due to the absence of coded current in section $A1T$ track relay $A1TR$ will now remain deenergized, and will cause signal SE to continue to display its stop aspect even though the train completely vacates section $A1T$.

When the train enters section $A2T$, track relay $A2TR$ will become deenergized and will cause signal SG to display its stop aspect. The deenergization of track relay $A2TR$ will also function through the medium of the decoding apparatus 10 to cause relay $A1CTM$ to operate at the rate of 75 times per minute, but this change in the rate of operation of relay $A1CTM$ will not have any effect on the remainder of the apparatus as long as any part of the train remains in section $A1T$.

However, as soon as the train vacates section $A1T$, the resultant removal of the train shunt permits the 75 code energy supplied to the rails of section $A1T$ to operate track relay $A1TR$. The first time relay $A1TR$ picks up and closes its front contact 11 , energy becomes stored in the transformer TF , and when this relay next releases and closes its back contact 5 , this stored energy causes a high voltage impulse to be supplied to the winding 8 of relay $A1HVR$ by virtue of the restoring circuit which is then closed at back contact 5 of relay $A1TR$ and at back contact $9-9b$ of relay $A1HVBSA$. This high voltage impulse causes relay $A1HVR$ to open its contact $17-17a$ and close its contact $17-17b$, whereupon relay $A1HVFSA$ picks up. Due to the previously described proportioning of the parts, the duration of this high voltage impulse is relatively short, and on the termination of this impulse the energy supplied to winding 15 of relay $A1HVR$ from battery 16 causes contact $17-17b$ to open and contact $17-17a$ to again close. Since contact 13 of relay $A1HVFS$ is closed when contact $17-17a$ becomes closed under these conditions, the closing of contact $17-17a$ completes the energizing circuit for relay $A1HVBSA$ and this relay then picks up. The picking up of this relay, in turn, interrupts the restoring circuit for relay $A1HVR$ and reestablishes the track circuit, so that subsequent operation of the track relay $A1TR$ in step with the coded current supplied to track section $A1T$ causes coded current of the same frequency to be supplied to section $A1T$. The proportioning of the parts is preferably such that the interruption of the restoring circuit for relay $A1HVR$ due to the picking up of relay $A1HVBSA$ will not occur during the duration of the high voltage impulse so that the contact $9-9b$ does not have to be a high voltage contact. The coded current supplied to section $A1T$ will cause track relay $A1TR$ to oper-

75

Although I have herein shown and described only two forms of signaling systems embodying my invention, it is understood that various changes and modifications may be made therein within the scope of the appended claims without departing from the spirit and scope of my invention.

Having thus described my invention, what I claim is:

1. In combination, a section of railway track, means for supplying coded signaling energy consisting of alternate "on" and "off" periods to the rails of said section, a track relay connected across the rails of said section and responsive to said coded energy, means for supplying to the rails of said section during each "on" period of the code a high voltage impulse of less duration than the "on" period to increase the shunting sensitivity of the track circuit formed by said track relay and the rails of said section, and means for detecting the presence of said high voltage impulse comprising a relay subjected to the track circuit energy and operable from one position to another if and only if said high voltage impulse is present during each "on" period.

2. In combination, a section of railway track, a coding relay having a first contact which is alternately opened and closed when said relay is operating and a second contact which becomes opened each time said first contact becomes closed, a source of track circuit current, an impulse transformer having its secondary winding connected across the rails of said section in series with said source and said first contact of said coding relay, a circuit for the primary winding of said impulse transformer including a source of current and said second contact, and a track relay connected across the rails of said section and responsive to the current supplied to the rails from said source of track circuit current over said first contact.

3. In combination, a section of railway track, means for supplying to the rails of said section coded signaling energy consisting of alternate "on" and "off" periods, each said "on" period having a high voltage impulse superimposed thereon, a checking relay subjected to said coded energy and operable in step with the code if and only if said high voltage impulse is present, and means controlled by said checking relay for interrupting the supply of coded energy to the rails of said section if said high voltage impulse is absent from the code.

4. In combination, a section of railway track, a coding relay having a first contact which is alternately opened and closed when said relay is operating and a second contact which becomes opened each time said first contact becomes closed, an impulse transformer having a primary and a secondary winding, a two winding polar stick checking relay; means comprising a source of track circuit current connected across the rails of said section in series with said first contact of said coding relay, the secondary winding of said impulse transformer, the one winding of said two winding checking relay, and a front contact of a first repeater relay for supplying coded signaling energy consisting of alternate "on" and "off" periods to the rails of said section, a track relay connected across the rails of said section and responsive to said coded signaling energy, means including a source of current and said second contact of said coding relay for energizing said primary winding to thereby induce in said secondary winding a high voltage

impulse during each "on" period of the code, means for constantly energizing the other winding of said checking relay, the parts being so proportioned that said checking relay will close a first polar contact during each "on" period of the code if and only if said high voltage impulse is present and a second polar contact at all other times, a second repeater relay, an energizing circuit for said second repeater relay including a source of current and said first polar contact, an energizing circuit for said first repeater relay including a source of current, said second polar contact and a front contact of said second repeater relay, and means for rendering said repeater relays sufficiently slow acting to maintain their armatures in their attracted positions whenever said checking relay is operating in response to the coded energy flowing in its said one winding.

5. In combination, a section of railway track, a coding relay having a first contact which is alternately opened and closed when said relay is operating and a second contact which becomes opened each time said first contact becomes closed, an impulse transformer having a primary and a secondary winding, a two winding polar stick checking relay; means comprising a source of track circuit current connected across the rails of said section in series with said first contact of said coding relay, the secondary winding of said impulse transformer, the one winding of said two winding checking relay, and a front contact of a first repeater relay for supplying coded signaling energy consisting of alternate "on" and "off" periods to the rails of said section, a track relay connected across the rails of said section and responsive to said coded signaling energy, means including a source of current and said second contact of said coding relay for energizing said primary winding to thereby induce in said secondary winding a high voltage impulse during each "on" period of the code, means for constantly energizing the other winding of said checking relay, the parts being so proportioned that said checking relay will close a first polar contact during each "on" period of the code if and only if said high voltage impulse is present and a second polar contact at all other times, a second repeater relay, an energizing circuit for said second repeater relay including a source of current and said first polar contact, an energizing circuit for said first repeater relay including a source of current, said second polar contact and a front contact of said second repeater relay, means for rendering said repeater relays sufficiently slow acting to maintain their armatures in their attracted positions whenever said checking relay is operating in response to the coded energy flowing in its said one winding, and a restoring circuit for said checking relay including said first contact of said coding relay, said source of track circuit current, the secondary winding of said impulse transformer, and a back contact of said first repeater relay.

6. In combination, a section of railway track, a first relay having a pair of contacts which are alternately opened and closed when said relay is operating, an impulse transformer having a primary and a secondary winding, a source of track circuit current connected across the rails of said section in series with one of the contacts of said first relay and the secondary winding of said transformer for supplying to the rails of said section coded signaling energy consisting of alternate "on" and "off" periods, a track relay

connected across the rails of said section and responsive to said coded current, a repeater relay provided with a contact and energized over the other contact of said first relay in such manner that said repeater relay will open its contact at the expiration of a short interval of time after said one contact of said first relay becomes closed, and means controlled by the contact of said repeater relay for energizing said primary winding of said transformer to thereby induce in said secondary winding during each "on" period of the code a high voltage impulse which increases the shunting sensitivity of the track circuit formed by the rails of said section and said track relay.

7. In combination, a section of railway track,

means for supplying coded signaling energy consisting of alternate "on" and "off" periods to the rails of said section, a track relay connected across the rails of said section and responsive to said coded energy, a two winding auxiliary relay having one winding connected across the rails of said section and the other winding connected with a source of current over its own front contact and a front contact of said track relay, the parts being so proportioned that said auxiliary relay will operate its contacts in step with the code if and only if said high voltage impulse is present during each "on" period of the code, and signaling means controlled by said auxiliary relay.

HOWARD A. THOMPSON.
